UNITED STATES PATENT OFFICE

WAINWRIGHT B. GERVAIS, OF CHICAGO, ILLINOIS

IRON-SUPPORTING STAND

Application filed June 25, 1928. Serial No. 288,139.

This invention relates to iron supporting stands and its object is the provision of a generally improved and simplified stand that may be economically produced.

Another object is to improve the insulation against objectionable heat conduction from the iron.

The invention is illustrated in the accompanying drawing, in which

10 Fig. 1 is a top plan view of a supporting stand embodying the present invention;

Fig. 2 is a side elevational view of the same; and

15 Fig. 3 is a vertical section taken on the line 3—3 of Fig. 1.

Referring to the drawing, the stand shown comprises a generally rectangular bottom sheet 5 preferably of asbestos and an upper sheet 6 also preferably of asbestos. The asbestos sheets 5 and 6 are of suitable thickness being preferably proportioned substantially as shown and the upper sheet 6 is spaced at 7 from the lower or base sheet 5 by suitable washers or spacers 8 also preferably of asbestos.

20 Although the bottom or base sheet 5 is shown as being of rectangular configuration, it is to be understood that this sheet may be shaped as desired. The upper sheet 6 is preferably shaped as shown in Fig. 1 to the general contour of a flat iron or other pressing iron and attached directly to the upper surface of the sheet 6 is a flanged retaining member 10 preferably in the form of a thin sheet

25 metal stamping resting directly upon the upper surface of the sheet 6 and provided with an up-turned marginal retention flange 12. The stamping 10 receives and supports the iron with the flange 12 marginally en-

30 circling or surrounding the iron and preventing accidental displacement of the same from the supporting stand. The configuration of the iron retaining stamping 10 preferably coincides with the configuration of the upper 35 asbestos sheet 6, although this may of course be varied as desired.

The stand is supported by feet 15 preferably formed of suitable insulating fiber and preferably of button-like configuration as 40 shown.

One of the feet 15 is shown in Fig. 1 as being positioned beneath each of the three corners of the upper sheet 6 and stamping 10 and each foot 15 is apertured at 16 and countersunk from the bottom at 18.

55 For the purpose of binding the sheets 5 and 6 together in spaced relation with the spaces or washers 8 between them and the feet 15 to the bottom of the sheet 5, I provide a plurality of bolts 20, one at each corner 60 of the sheet 6. The heads 21 at the upper ends of the bolts 20 are preferably countersunk into the sheet 6 and preferably lie substantially flush with the upper surface of the stamping 10. The material of the stamping 10 is turned down conically around the openings 22 through which the shanks of the bolts 20 extend as at 23, and these conically turned down portions 23 are clamped beneath the heads 21 so that the bolts 20 thereby have 65 the additional function of clamping the stamping 10 firmly upon the upper surface of the insulating sheet 6. The shanks of the bolts 20 extend on down through registering openings in the washers or spacers 8 and sheet 70 5 and on through the openings 16 in the feet 15, and have threaded engagement at their lower ends with nuts 25 disposed in the counterbored sockets or recesses 18 in the lower ends of the feet 15. The nuts 25 are drawn 75 up to clamp the feet 15 firmly to the bottom of the sheet 5 and all parts firmly together 80 into a unitary stand.

85 The stand is of simple and economical construction and the structure illustrated and described provides good insulation against objectionable heat conduction from the iron.

90 The feet 15, which, as already pointed out, are preferably of suitable insulating fiber, support the stand and, at the same time, space 95 the sheet 5 upwardly from the supporting surface with the open cooling space 26 therebeneath and the spacing of the sheet 6 from the sheet 5 provides the additional open cooling space 28. In addition, the sheets 5 and 6 form heat insulating barriers between the iron supported upon the stamping 10 and the support upon which the feet 15 are mounted.

100 The bottom sheet 5 is preferably provided

marginally with a metallic binder 30 which may be of channel section with the flanges 32 and 33 turned over upon the upper and lower surfaces, respectively, of the sheet 5. The corners of the binder 30 may be mitered and suitably joined or secured together at 34 providing a continuous binder about the margin of the sheet 5 and self-retained thereon. Of course, rivets or other securing elements may be provided for securing the binder 30 to the margin of the lower sheet 5.

The resulting stand is of good stability and the enlarged size of the lower sheet 5, as compared with the upper sheet 6, provides a projecting ledge horizontally around and below the sheet 6 and iron supporting plate or stamping 10. This projecting ledge prevents positioning the heated iron as supported upon the plate or stamping 10 objectionably close to adjacent objects and, at the same time, permits conveniently grasping the lower sheet 5 for the purpose of moving or changing the position of the stand with the heated iron in place thereon.

25 Due to the asbestos structure of the sheets 5 and 6 and to the asbestos structure of the washers or spacers 8, as well as to the insulating fiber structure of the feet 15, objectionable heat conduction to these parts is eliminated or 30 reduced and the countersinking on the nuts 25 up into the recesses 18 in the feet 15 eliminates any objectionable heat conduction through the bolts or securing elements 20 to the supporting surface upon which the stand 35 is mounted as indicated by the line 35 in Fig. 3.

I do not intend to be limited to the precise details or configurations shown or described.

I claim:—

40 1. An iron supporting stand, comprising a pair of vertically separated plates, one of said plates being of the general contour of the iron to be supported and adapted for receiving and supporting the iron and the other of said 45 plates being of a size larger than said first plate to form a ledge projecting horizontally beyond the margin of said first plate.

2. An iron supporting stand, comprising a pair of vertically separated plates, one of said 50 plates being of the general contour of the iron to be supported and adapted for receiving and supporting the iron and the other of said plates being of a size larger than said first plate to form a ledge projecting horizontally 55 beyond the margin of said first plate, and supporting feet beneath said larger plate.

3. An iron supporting stand, comprising a pair of vertically separated plates, one of 60 said plates being of the general contour of the iron to be supported and adapted for receiving and supporting the iron and the other of said plates being of a size larger than said first plate to form a ledge projecting horizontally 65 beyond the margin of said first plate,

said plates being formed of heat insulating material.

4. An iron supporting stand, comprising a pair of vertically separated plates, one of said plates being of the general contour of the iron to be supported and adapted for receiving and supporting the iron and the other of said plates being of a size larger than said first plate to form a ledge projecting horizontally beyond the margin of said first plate, 70 said plates being formed of heat insulating material, and a thin metal sheet covering the upper surface of the upper plate and attached thereto, said sheet having an 75 upward marginal flange.

In witness whereof, I hereunto subscribe my name this 21 day of June, 1928.

WAINWRIGHT B. GERVAIS.
